APPARATUS FOR DEVELOPING

Jean Breton, Bellevue, France

Application January 8, 1932, Serial No. 585,521
In Belgium January 17, 1931

5 Claims. (Cl. 95—89)

The present invention relates to apparatus for developing and, more particularly, to those of the type in which ammonia is employed as developing reagent.

5 One of the objects of the invention is to provide a novel apparatus for developing with ammonia vapor wherein heat is applied during the course of development.

Another object is to provide a special form 10 of machine in which the ammonia is swept out of the developing chamber prior to the opening thereof.

Still another object is to provide a duplex type 15 of machine in which two developing chambers are alternately traversed by a current of ammonia and by a scavenging air current.

A further object is to provide safety means 20 for insuring against opening of a developing chamber while the latter is being traversed by a current of ammonia.

An additional object is to provide a valve assembly for a duplex developing machine permitting either one of two developing chambers to be supplied with ammonia or with air, auxiliary means being associated with the valve assembly 25 for preventing rotation thereof while ammonia is traversing either one of the developing chambers.

Another object still is to provide a special 30 generating assembly for mixing ammonia with air, said assembly including means for forming an emulsion of air and ammonia solution and for subsequently separating the emulsion into its constituents i.e. ammonia laden air and ammonia solution.

Still another object is to provide an apparatus 40 permitting heating of an ammonia solution while the air is passing therethrough so as to enrich the ammonia content of the air, said apparatus further permitting cooling of the ammonia solution so as to favour reabsorption of ammonia by the solution.

Still further objects will appear in the course 45 of the detailed description now to be given with reference to accompanying drawings, in which:

Fig. 1 is a side view, partially in section (the section is taken on line 1—1 of Fig. 2) of one illustrative embodiment of the invention;

Fig. 2 is a section taken on line 2—2 of Fig. 1; 50 Fig. 3 is an end view of the apparatus represented in Figs. 1 and 2;

Fig. 4 is a diagrammatic section through a second form of the invention;

Fig. 5 represents, in elevation, the duplex form 55 of machine represented in Fig. 4;

Fig. 6 shows a section taken on line 6—6 of Fig. 5;

Fig. 7 shows a detail of construction as seen in a section taken on line 7—7, of Fig. 5;

Fig. 8 is a plan view, partially in section, of 60 the apparatus represented in Figures 4, 5 and 6.

Referring to Figures 1 to 3 of the drawings, there is shown an assembly composed of the following elements: a developing chamber *a* having resistance heating elements *a'* buried in the walls thereof; an end enclosure *b* having an opening therein permitting the passage of a motor shaft; a second end enclosure *c* provided with an observation window (not shown) and some such locking device as is represented in the drawings; 65 a container for ammonia solution *d* having an air inlet tube *d'* extending thereinto and being provided with an outlet port *d''*; a screen *e'* positioned inside cylinder *a* and serving to prevent undue movement of objects inside the latter; 70 means for circulating gases through cylinder *a*, including a first three way valve *k*² capable of establishing communication between (1) the outside air and an inlet port *e*² positioned adjacent one end of cylinder *a* or (2) between one arm of 75 cylinder *a* and a conduit *f* connecting port *e*² to outlet port *d*² of container *d*—a second three way valve *k*¹ controlling the intersection between a discharged conduit *g*, inlet tube *d'* and a chimney *j*—an outlet port *e'* establishing communication between 80 cylinder *a* and discharged conduit *g*—and a single control handle *l* mounted to simultaneously rotate valves *k*¹ and *k*², said valves and said valve handle being assembled so that when valve *k*² permits the entrance of the outside air, gases 85 passing through discharge conduit *g* are deflected by valve *k*¹ upward into chimney *j*, while when handle *l* is turned to cut off the outside air and to establish communication via *d*², *f*, *e*², valve *k*¹ deflects the gases traversing conduit *g* downward 90 into container *d* via inlet conduit *d'*.

The herein above described assembly operates in the following manner: assuming ammonia solution to be charged into container *d* and cylinder *a* to be in closed position as shown in Figures 100 1 and 2, when handle *l* is turned to permit circulation of gases from container *d* through conduit *f* toward port *e*² and motor *i* is set in motion, air will be drawn through inlet conduit *d'* into the solution inside container *d*; the air traversing said solution, laden with ammonia will then pass through port *d*² and into cylinder *a* via *f*, *k*², *e*² and development will begin; during the latter process, the circuit through heating resistances *a'* may be closed in order to hasten development; 110

as soon as developing has progressed sufficiently, the circuit through resistance a' may be opened and valve handle l turned so as to cut off communication between points d^2 and e^2 , while permitting air to enter via valve k^2 ; because of simultaneous rotation of valve k' , air will be drawn through cylinder a , and will discharge, through port e^1 into discharge conduit g^1 whence it will be deflected upward into chimney f instead of downward into container d ; when the ammonia vapours have been thoroughly scavenged, port c may be opened and the developed photographic material removed.

In the duplex form of machine shown in Figures 4 to 8, a pair of vertical cylinders a^1 and a^2 similar to the one already described and provided with supporting bases b^1 , b^2 and hinged closures c^1 , c^2 are connected to a valve system operating to establish circulation of ammonia vapours through one cylinder while automatically establishing circulation of the air through the other.

The valve assembly is composed of a stationary plate m having ten ports formed therein divided into two groups of five, the first group being composed of a central port n communicating with an evacuation conduit and flanked by (1) a pair of ports n^1 , n^2 communicating via a pair of conduits o^1 , o^2 with one of the extremities of cylinders a^1 and (2) a second pair of ports n^{10} , n^{20} communicating via a pair of conduits o^{10} , o^{20} with the inlet port d^1 of an ammonia reservoir to be described further on,—the second group being similarly composed of a central port p communicating via a conduit q with the outlet of said ammonia reservoir, and flanked by (1) a first pair of ports p^1 , p^2 , communicating through the intermediary pair of conduits k^1 , k^2 with the opposite extremities of cylinders a^1 , a^2 and (2) by a second pair of ports p^{10} , p^{20} communicating with the outside air,—the assembly being completed by a rotatable plate r provided with an appropriate handle and maintained in assembled relation with stationary plate in any convenient way, rotatable plate r being capable of occupying either one or two different positions and being provided with four recesses r^3 , r^4 , r^5 and r^6 (shown in dotted lines in Figure 4) positioned so as to establish communication (1) between the central port of each group and those next adjacent (for example, n^1 of one group and p^2 in the other) and (2) between the two lateral ports on the other side of the central port relatively to said last named next adjacent port (for example, n^2 and n^{20} in one group and p^1 and p^{10} in the other).

55 The valve assembly and conduits are connected in series with a pair of independent circulating fans mounted to be driven by a single motor i .

The circulating system is provided with means (1) for preventing opening of cylinders a^1 or a^2 while being traversed by ammonia and (2) for preventing rotation of valve element r while either of said cylinders is open.

The former of these two means consists of a pair of ears t^1 , t^2 mounted on element r so that when the latter is moved into position for sending a current of ammonia into any given cylinder, one of said ears moves into contacts with the corresponding end closure c^1 , or c^2 so as to prevent an opening movement of the latter (each of said closures may be provided with counter-weights such as s^1 , s^2 and screws of some such conventional form as is shown in Fig. 7 for insuring a firm locking-action).

The second above mentioned means includes a pair or spring actuated movable fingers u^1 and u^2

positioned in the path of movement of ears t^1 , t^2 and capable of forming abutments for said ears, said fingers acting to prevent rotation of element r while in raised position, and being maintained in lowered position when the corresponding end closure is closed. It will be seen therefor, that opening of the latter prevents rotation of element r .

The manner in which this form of apparatus operates is practically evident from the foregoing description, rotation of element r into one of the other of two positions establishing a flow of ammonia through one cylinder while simultaneously introducing air into the other.

This form of apparatus may be equipped with some such conventional form of ammonia reservoir as is shown in Figures 1 and 2. Preferably, however, the special form of reservoir assembly shown in Figs. 4 to 6 (see particularly Fig. 6) should be employed. This special form of assembly is characterized by the fact that an emulsion of air and ammonia solution is successively formed and broken up so as to ensure thorough saturation of the air with ammonia, auxiliary means being further provided for heating and cooling the ammonia solution so as to favour volatilization and reabsorption of the ammonia.

Referring to Figs. 4 to 6, there is shown an ammonia volatilizing assembly or generator composed of the following elements: a container d divided into an upper and lower compartment A and B by either a partition (not shown) or by a fixed bell C fitting into the container so as to leave a lateral passage K , the upper wall of the bell supporting an outlet tube F , G , portion G extending into compartment E and having a plurality of orifices formed therethrough, and portion F extending upward through compartment B into a glass bell H ; a conduit E forming a prolongation of conduits o^{10} , o^{20} and connecting the latter to the upper portion of lower compartment A ; a resistance d^3 mounted inside compartment A and extending up into tube G , said resistance serving to heat the ammonia solution adjacent thereto; a pair of small tubes I and J open at their upper ends and having small holes formed therethrough at their bases, said tubes being positioned in an annular opening around tube F at the point where the latter traverses the top of compartment B , tube I containing a thermometer and tube J containing a Beaumé aermeter capable of registering the concentration of the circulating liquid; a float M mounted in compartment B and having an indicating rod attached thereto extending into glass-bell H at a point adjacent tube F ; a tube O extending into a compartment A and serving to permit discharge of the gases under bell B when the gaseous pressure inside the latter, for any reason, exceeds any predetermined value (for example, because of excessive heating of resistance d^3); and a bent tube L provided with a plug L^1 serving to fill or empty (by siphoning) chamber A .

The above described assembly operates in the following manner: when air is introduced under pressure through tube E , liquid is forced up into compartment B and tube F ; when the amount of air in compartment A becomes sufficient, it will pass through the perforations of tube G together with a certain amount of ammonia solution and the emulsion thus formed will rise into tube F , overflow inside bell H , and pass downward via the annular space surrounding tube F into compartment E ; on arriving in compartment B , the emulsion breaks up into a gaseous portion

which escapes through outlet port d^2 and is delivered to one of the developing cylinders while the liquid portion remaining flows downward through passage k into compartment A and repeats the cycle.

Rod N, attached to float M, indicates the amount of liquid in the apparatus which may be filled to any desired level through bent tube L. If it be desired to empty container b, it is only necessary to unscrew plug L¹, introduce a siphon into tube L, and set ventilator h in motion, the latter acting to start the siphon.

The invention is not to be taken as limited to the particular structures shown; thus, the form of ammonia generator or reservoir represented in Fig. 6 may be used interchangeably with the one illustrated in Fig. 1, the latter including heating and cooling elements as may be desired.

While no cooling elements have been shown in the form of apparatus represented in Fig. 6, the latter should be provided with a cooling serpentine, cooling ribs or equivalent structure permitting the solution in container d to be cooled when it be desired to reabsorb ammonia vapours passing therethrough, heating resistance d^3 serving to liberate the ammonia solution during the periods of volatilization.

What I claim is:—

1. In a photograph developing assembly, a pair of developing chambers, a reagent generator mounted to communicate with said chambers, means for establishing a current of gas through said chambers, and a valve assembly operative to establish communication between said generator and one of said chambers while simultaneously cutting off communication between the latter and the other of said chambers, said valve assembly further operating to establish communication between the atmosphere and the chamber cut off from the generator, whereby air may be aspirated through said last named chamber by said means for establishing a current of gas.

2. In a developing machine, a chamber, a container adapted to contain ammonia solution up

45

to a given level, a first conduit extending from said chamber to a point of said container situated below said level, a second conduit extending from a point of said container situated above said level to said chamber, means connected to one of said conduits for establishing a flow of gas through the circuit constituted by said chamber, said conduits and said container, a valve operative to establish and to cut off communication between the atmosphere and said chamber, and a valve connected to the same conduit as said means and operative to establish and to cut off communication between said circuit and the atmosphere at a point situated on said last named conduit on the other side relatively to aforesaid means than said chamber.

3. A structure as defined in claim 2 in combination with valve means operative to establish and to cut off communication between said chamber and said container.

4. In a photograph developing assembly, a pair of developing chambers, a reagent generator mounted to communicate with said chambers, means for establishing a current of gas through said chambers, a valve assembly operative to alternately connect one of said chambers in communication with said generator while simultaneously cutting off communication between said generator and the other of said chambers, and means operative to prevent opening of the chamber communicating with said generator via said valve assembly.

5. In a photograph developing assembly, a pair of developing chambers, a reagent generator mounted to communicate with said chambers, means for establishing a current of gas through said chambers, a valve assembly operative to alternately connect one of said chambers in communication with said generator while simultaneously cutting off communication between said generator and the other of said chambers, and means operative to prevent actuation of a valve assembly while one of said chambers is open.

JEAN BRETON.
